UNITED STATES PATENT OFFICE.

ANTON BECKER, OF COLUMBUS, OHIO, ASSIGNOR TO THE RALSTON STEEL CAR COMPANY,
OF COLUMBUS, OHIO.

UNDERFRAME CONSTRUCTION FOR RAILWAY-CARS.

1,264,884.

Specification of Letters Patent.

Patented May 7, 1918.

Application filed July 11, 1916. Serial No. 108,726.

To all whom it may concern:

Be it known that I, ANTON BECKER, a citizen of the United States, and a resident of Columbus, in the county of Franklin and 55 State of Ohio, have invented certain new and useful Improvements in Underframe Constructions for Railway-Cars; and I do hereby declare the following to be a full, clear, and exact description of the invention, 10 such as will enable others skilled in the art to which it appertains to make and use the same.

This invention relates to improvements in underframe construction for railway cars, 15 and more particularly to the connections of the transverse beams with the center girder members,—one object of the invention being to provide simple and efficient means whereby the underframe members may be readily 20 assembled in proper alinement and effectually secured and supported.

With this and other objects in view, the invention consists in certain novel features as hereinafter set forth and pointed out in 25 the claim.

In the accompanying drawings; Figure 1 is a transverse sectional view of a car underframe embodying my improvements; Fig. 2 is a view partly in plan and partly in section 30 of a portion of the underframe; Fig. 3 is a sectional view on the line 3—3 of Fig. 2, and Figs. 4 and 5 are detail views of one of the brackets 8.

1, 1 represents the center girder members 35 forming, with a cover plate 2 secured to said members by means of angle beams 2^a, a box girder. The respective center girder members are provided with openings to permit the passage of continuous transverse beams 40 which, in the present instance, are preferably made in the form of I-beams 3. Each transverse beam or member 3 is secured at its respective ends to the side sills 4 of the underframe by means of angle brackets 5,—the latter being securely riveted to the side sills 45 and to the transverse beams and formed with pockets 6 to receive the upper flanges of the latter,—the lower flanges of the transverse beams being cut away at the ends of each 50 beam and the outer ends of the latter being disposed between the flanges of the side sills, as shown in Fig. 1.

Angle bars 7 are riveted to the outer faces of the center girder members in position to receive and support the continuous transverse I-beams 3.

A flanged bracket 8, preferably of pressed steel, is located at the juncture of each transverse beam with the respective center girder members. Each connecting bracket 8 comprises a web portion 9, a vertical flange 10 and upper and lower flanges 11—12,—each of which latter are made with depressed portions 13 for the accommodation of the flanges of the transverse I-beam.

Connecting brackets, such as above described are located at respective sides of each transverse I-beam at the juncture of the latter with the center girder members, as shown in Fig. 3,—the web portions of said brackets lying against the web portion of the I-beam and securely riveted thereto as shown in Fig. 1. The vertical flanges of the connecting brackets are riveted to the center girder members as shown in Figs. 1 and 3 75 and the lower flanges 12 of said brackets rest upon and are riveted to the supporting angle bars 7.

With my improvements, the lining-up of the transverse beams is greatly facilitated. 80 The supporting angle bars 7 may first be secured in place and in accurate alinement on the center girder members. The transverse beams may then be passed through the center girder members and supported upon said angle bars,—after which the pressed connecting brackets may be placed in position and riveted to the transverse beams and the center girder members as previously explained. Thus it will be seen that efficient 85 means are provided for positively supporting the transverse beams while the connecting brackets are being secured in place, and the accurate assembling of the underframe is greatly facilitated.

Having fully described my invention what I claim as new and desire to secure by Letters-Patent, is:—

In a car underframe, the combination with a center girder, and a transverse I-beam passing through the center girder, of an angle bar secured to the center girder in position to support said I-beam, connecting brackets secured at respective sides of said I-beam,

said brackets having vertical flanges secured to the center girder, said brackets also having upper and lower flanges formed with depressions to receive the flanges of the I-beam, and the lower flanges of said brackets secured to the angle bars.

In testimony whereof, I have signed this

specification in the presence of two subscribing witnesses.

ANTON BECKER.
